UNITED STATES PATENT OFFICE.

CARL J. SCHWARZE, OF ADRIAN, MICHIGAN, ASSIGNOR TO SCHWARZE ELECTRIC COMPANY, OF ADRIAN, MICHIGAN, A CORPORATION OF MICHIGAN.

ELECTRICALLY-OPERATED SOUND-PRODUCER.

1,180,444.

Specification of Letters Patent. Patented Apr. 25, 1916.

Application filed May 29, 1914. Serial No. 341,741.

To all whom it may concern:

Be it known that I, CARL J. SCHWARZE, a citizen of the United States of America, residing at Adrian, in the county of Lenawee and State of Michigan, have invented certain new and useful Improvements in Electrically-Operated Sound-Producers, of which the following is a specification, reference being had therein to the accompanying 10 drawings.

The invention relates to electrically operated sound producers more particularly designed for use on vehicles, and the invention consists in certain features of construction 15 as hereinafter set forth.

In the drawings: Figure 1 is a perspective view. Fig. 2 is an end elevation with the cap removed; Fig. 3 is a longitudinal section through the sound producer; Fig. 4 20 is a plan view of a portion of the sound producing diaphragm showing the reinforcement therefor; and Fig. 5 is a section on line $x-x$ Fig. 4.

My improvement applies to sound producers of that type in which a vibratory diaphragm is actuated by a striker, which in turn is reciprocated by electro-magnetic means. The sound produced is intensified by a resilient buffer which is opposed to the 25 resilient diaphragm, and in connection therewith has the effect of increasing the amplitude of vibration of the striker.

It is one of the objects of the invention to overcome a defect in constructions heretofore used, viz., the cracking of the diaphragm at the point of contact of the striker thereon. It has been found that these diaphragms very frequently develop radially-extending checks which start from the point 30 of impact, so as to interfere with the proper vibration and the quality of sound produced. This defect I have overcome by arranging at the point of impact a reinforced or trussed section which is relatively rigid 40 and initiates the vibratory movement at a point further from the center.

It is another feature of the invention to obtain a construction which may be used upon motor vehicles, and in which the switch 45 or push-button is mounted upon the casing which incloses the sound producer.

In detail, A is the casing for inclosing the operating parts and which is provided with a forwardly-projecting horn B.

C is the vibratory diaphragm extending

across the casing adjacent to the forward end thereof.

D is a reciprocatory striker for impinging upon the diaphragm C, E is an electro-magnet, and F is a vibratory armature actuated 60 thereby and which is connected with the striker D. To avoid injury to the diaphragm at the point of impact, a reinforced or trussed section is provided, this being preferably formed by embossing the center 65 of the diaphragm, as shown at G. This will stiffen the structure so that the blow of the striker will produce an opposite movement of this portion, initiating the flexing of the diaphragm at a point removed from the 70 center. The result is that the metal is not over-strained and checking is thereby avoided.

The armature F is hinged to a cross bar H of the frame, which is apertured for the 75 passage of the striker D. The striker is also further guided by a tubular support I arranged between the coils of the magnet, this being of the horseshoe type.

J is a spring arm which engages a 80 shoulder K on the striker and holds the same in contact with the armature F and presses the latter toward the resilient buffer L.

M is a spring contact member which cooperates with a contact point N on a metallic arm O to close the electric circuit, while the movement of the armature operates these contacts to open the circuit. To form a simple circuit closer for operating the sound producer a push-button P is arranged in a 90 central embossed portion Q of a removable cap R forming a portion of the casing. This push-button bears against an insulated spring contact member S, the free end of which extends in proximity to the member 95 O, and the arrangement is such that by pressing against the button the member S is pressed into contact with the member O to close the electric circuit.

The sound producer where used for a motor cycle is preferably mounted upon the handle-bar or in some other convenient location where the push-button P may be easily reached. As shown, an arm T is riveted or otherwise secured to the casing A and is 105 provided with a clip plate U which may be clamped by bolts V upon the handle-bar.

What I claim as my invention is:—

The combination with a casing, of electro-magnetically operated sound producing 110

means inclosed therein including a diaphragm and a striker, a horn extending forward from said casing and arranged centrally of the diaphragm, said diaphragm having an inwardly embossed portion against which the striker impinges, said inwardly embossed portion being substantially in axial alinement with the horn, a pushbutton projecting from said casing on the op-

posite side of said horn and arranged centrally of said casing, and a circuit closure operated by the said pushbutton.

In testimony whereof I affix my signature in presence of two witnesses.

CARL J. SCHWARZE.
